CLAIM

I claim the ornamental design for a holder, as shown and described.

DESCRIPTION

FIG. 1 is a front/right/top perspective view of a holder (a front/left/top perspective view would be a mirror image thereof);

(Continued)

FIG. 2 is a rear/left/bottom perspective view thereof (a rear/right/bottom perspective view would be a mirror image thereof);

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines adjacent the contour lines represent the bounds of the claimed design, while all other broken lines depict environmental subject matter only and form no part of the claimed design. None of the broken lines form any part of the claimed design.
